UNITED STATES PATENT OFFICE.

JAMES NUTTALL, OF NEW ORLEANS, LOUISIANA.

IMPROVEMENT IN IRON TIES FOR COTTON-BALES.

Specification forming part of Letters Patent No. **23,940**, dated May 10, 1859.

To all whom it may concern:

Be it known that I, JAMES NUTTALL, of the city of New Orleans, State of Louisiana, have made a new and useful Improvement in Ties for Iron Bands for Cotton-Bales; and I hereby declare the following is a full, clear, and exact description thereof, reference being had to the accompanying drawings, and to the letters of reference marked thereon, making a part of this specification—the same letters being used to designate the same parts shown in the respective figures.

Figure 1 is a side or top view. Fig. 2 is an end view. Fig. 3 is a sectional edge view.

The ends of the band to be joined are marked A and B, and the part where the attachment is made marked *a b*, as shown more particularly in Fig. 3, the clasp which confines the hooks in this figure being omitted purposely, so the form of the hooks, as caught in plate S, can be seen, being each separately hooked in the mortise *m* in the plate. The hook *a* is supposed to be a permanent one—that is, any changes to be made in the length of the band, this hook is not disturbed, the clasp *c* being passed over plate *s* and hook *a* when the tie

is being made and set down against the shoulders on the edges and at one end of plate *s*. (See Fig. 1.) When the clasp is so placed, the mortise in the plate is uncovered to allow the end of the band *B* to be passed through the mortise, and when drawn taut, the end lapped down on the plate, thus making the hook *b*. The clasp, being moved over both hooks, holds them firm. In compressing the bale, moving the clasp, as stated, off hook *b* allows that end to be again drawn through the mortise and allow another hook to be made, as has been stated.

After this my description, what I claim as new, and desire to secure by Letters Patent, is—

The combination of the plate *s* and movable clasp *c*, when made use of in confining the hooks *a* and *b* as a fastening for iron ties for cotton-bales, when made and arranged the same or substantially as has been set forth.

JAS. NUTTALL.
